CLAIM

We claim as our invention the ornamental design for a garlic tray, as shown and described herein.

DESCRIPTION

FIG. 1 is a side, perspective, exploded view of a garlic tray having a lid portion, a middle portion, and a container portion;

FIG. 2 is a side view of the garlic tray with the lid, middle, and container portions nested, and the lid portion;

FIG. 3 is a bottom view of the garlic tray with the lid, middle and container portions nested, and the lid portion;

FIG. 4 is a top, perspective view of the garlic tray with the lid, middle, and container portions nested, and the lid portion;

FIG. 5 is a side perspective view of the garlic tray with the lid, middle, and container portions nested, and the lid portion;

FIG. 6 is a top view of the garlic tray with the lid, middle, and container portions nested, and the lid portion;

FIG. 7 is a bottom view of the garlic tray with the lid, middle, and container portions nested;

FIG. 8 is a side, exploded view of the garlic tray having a lid portion, a middle portion, and a container portion;

FIG. 9 is an end, exploded view of the garlic tray having a lid portion, a middle portion, and a container portion;

FIG. 10 is a top, perspective view of the lid portion;

FIG. 11 is a bottom, perspective view of the lid portion;

FIG. 12 is a top view of the lid portion;

FIG. 13 is a side view of the lid portion;

FIG. 14 is an end view of the lid portion;

FIG. 15 is a bottom view of the lid portion;

FIG. 16 is a perspective view of the middle portion;

FIG. 17 is a bottom, perspective view of the middle portion;

FIG. 18 is a top view of the middle portion;

FIG. 19 is a side view of the middle portion;

FIG. 20 is an end view of the middle portion;

FIG. 21 is a bottom view of middle portion;

FIG. 22 is a perspective view of the container portion;

FIG. 23 is a top view of the container portion;

FIG. 24 is a side view of the container portion;

FIG. 25 is an end view of the container portion; and,

FIG. 26 is a bottom view of the container portion.
